TRASH RECEPTACLE OR THE LIKE

Raymond J. Mangold, Montville, and Clayton S. Myers, Fanwood, N.J., assignors, by mesne assignments, to Contico International, Inc., St. Louis, Mo., a corporation of Missouri

Filed July 25, 1968, Ser. No. 12,893

Term of patent 14 years

Int. Cl. D7—06

U.S. Cl. D49—35

FIG. 1.

FIG. 3.

FIG. 2.

FIG. 4.

FIG. 1 is an isometric view of a receptacle showing our new design;

FIG. 2 is a top plan view of the receptacle of FIG. 1 on a reduced scale;

FIG. 3 is a cross-sectional view taken along line 3-3 of FIG. 2;

FIG. 4 is a bottom plan view of the receptacle of FIG. 1 on a reduced scale.

We claim:

The ornamental design for a trash receptacle or the like, substantially as shown.
